Primary Examiner — Stella Reid*Assistant Examiner* — Elizabeth J Oswecki(74) *Attorney, Agent, or Firm* — Booth Udall, PLC; Steven J. Laureanti(57) **CLAIM**

The ornamental design for an ornamental wrap, as shown and described.

DESCRIPTION

FIG. 1 is a perspective view of an ornamental wrap according to the present invention;

FIG. 2 is a front view of the ornamental wrap of FIG. 1; FIG. 3 is a back side view of the ornamental wrap of FIG. 1; FIG. 4 is a left side view of the ornamental wrap of FIG. 1; FIG. 5 is a right side view of the ornamental wrap of FIG. 1. FIG. 6 is a top view of the ornamental wrap of FIG. 1; and, FIG. 7 is a bottom view of the ornamental wrap of FIG. 1. The broken lines showing of a bucket and a handle in FIG. 1 are included for illustrative purposes only and form no part of the claimed design.
